Emanuel Schreck, 277 5th Ave., New York, N.Y.

Filed Jan. 12, 1960, Ser. No. 59,017

Term of patent 3½ years

(Cl. D88—3)

FIG. 1 is a bottom perspective view of an umbrella showing my new design.

FIG. 2 is a top plan view; and

FIG. 3 is a reduced side elevational view thereof.

The dominant features of my design reside in the portions shown in full lines.

I claim:

The ornamental design for an umbrella, substantially as shown and described.
